United States Patent Office

Des. 182,953
Patented June 3, 1958

182,953

PHONOGRAPH RECORD HOLDER OR THE LIKE

Harold R. Gullixson, Greensboro, N. C.

Application March 29, 1957, Serial No. 45,505

Term of patent 14 years

(Cl. D33—3)

FIG. 1.

Des. 182,953

PAGE 2

FIG. 3.

FIG. 4.

The broken line indication of records in Figure 2 is for illustrative purposes only.

I claim:

The ornamental design for a phonograph record holder or the like, substantially as shown and described.
